(57) **CLAIM**

The ornamental design for an electronic device, as shown and described.

DESCRIPTION

FIG. 1 is a first side view of an electronic device showing our new design;

FIG. 2 is a second side view thereof, rotated by 45° clockwise from the first side view;

FIG. 3 is a third side view thereof, rotated by 90° clockwise from the first side view;

FIG. 4 is a fourth side view thereof, rotated by 135° clockwise from the first side view;

FIG. 5 is a fifth side view thereof, rotated by 180° clockwise from the first side view;

FIG. 6 is a sixth side view thereof, rotated by 270° clockwise from the first side view; and,

FIG. 7 is a top view thereof.

(Continued)

The broken lines illustrate boundaries which form no part of the claimed design and the relatively light portions therein illustrate portions of the electronic device which form no part of the claimed design.
